UNITED STATES PATENT OFFICE.

CHARLES E. DATH, OF CHICAGO, ILLINOIS, ASSIGNOR TO WILLIAM H. MINER, OF CHAZY, NEW YORK.

RAILWAY DRAFT RIGGING.

Application filed September 18, 1920. Serial No. 411,317.

To all whom it may concern:

Be it known that I, CHARLES E. DATH, a citizen of the United States, residing at Chicago, in the county of Cook and State 5 of Illinois, have invented a certain new and useful Improvement in Railway Draft Riggings, of which the following is a full, clear, concise, and exact description, reference being had to the accompanying drawings, 10 forming a part of this specification.

This invention relates to improvements in railway draft riggings.

In many foreign countries, particularly 15 countries of Europe and Asia, it has been, and still is, the common practice to employ couplings between cars of the so-called hook type and wherein the coupling has a cylindrical shank at its inner end to which is applied a heavy nut, the latter acting in 20 the manner of a rear follower in cooperation with a draft spring. At the present time, there is going on a gradual transition from the type of coupling above mentioned to the more modernized and efficient automatic type of coupling such as has been 25 standardized in the United States and Canada. Along with the transition in the form of couplings, an effort is being made to substitute shock absorbing units of the type 30 now universally employed in the United States which are operable in both buff and draft for the older arrangements, wherein separate shock absorbing units are employed, one for draft and one or more for 35 buffing.

The object of my invention is to provide a simple and economical construction which will permit of the use of either the standardized automatic couplers of the American 40 type or the foreign hook type of coupling, interchangeably with a draft gear proper of the pull and buff arrangement. More specifically, the object of my invention is to provide an arrangement permitting of interchangeable use of automatic couplers and hook couplings with a draft rigging employing a yoke of the key type in connection with a coupler or draw bar.

In the drawings forming a part of this 50 specification, Figure 1 is a vertical longitudinal sectional view of a portion of a railway car of a type now in use in certain foreign countries showing my improvements in connection therewith. Figure 2 55 is a horizontal sectional view of the struc-

ture illustrated in Figure 1 and corresponding substantially to the line 2-2 thereof. In both Figures 1 and 2, a hook type of coupling is shown in full lines and an automatic coupler is indicated in dotted lines, 60 which more clearly illustrates the interchangeable features of my improvements. Figure 3 is a vertical transverse sectional view corresponding substantially to the line 3-3 of Figure 1. And Figure 4 is a detail 65 perspective of a special member employed in carrying out my invention.

In said drawings, the draft sills are shown as comprising a pair of upper relatively shallow channels 10-10, the effective 70 depth of which is increased by securing thereto angle irons 11-11 along the bottoms thereof. To the inner faces of the built-up draft sills above described are secured two stop castings or cheek plates 75 12-12, each of which is formed with a pair of stop shoulders 13-13 and an integral upper follower guiding flange 14. The lower follower guiding flanges 15-15 are in the nature of detachable straps adapted 80 to be bolted to the castings 12 as by the bolts 16-16. The shock absorbing unit shown is of the buff and draft type and employs a front follower 17, rear follower 18 and a spring 19. 85

Connected with the draft gear, I have shown a yoke of well-known form, the same being of the so-called hooded type. Said yoke comprises a U-shaped strap 20 which encircles the shock absorbing unit and a hollow substantially rectangular cast hood 21, the latter having forwardly flaring side walls 22-22 slotted as indicated at 23-23 to receive a coupler key 24. The upper and lower walls of the hood 21 are longitudinally slotted, as indicated at 124, to receive the forward ends of the arms of the strap 20, the arms and the hood being united by short rivets 25-25 placed under double shear, as clearly indicated in Figure 1. 90

At the end of the car construction, a channel-shaped end sill 26 is employed, the same being cut away, as indicated at 27, to accommodate the draw bar or coupler. A buffing plate in the form of an angle 28 is also employed and a special form of detachable carry iron 29, the latter providing a horizontally extending supporting surface indicated at 30. 95

A hook type of coupling is indicated at 110

31, the same being constructed as now commonly employed in many foreign countries. Said coupling 31 has a cylindrical shank 32, the rear end of which is threaded, as indicated at 33, to adapt it for the reception of a heavy nut in a manner now customary. In carrying out my invention, the shank 32 is preferably notched on its under side, as indicated at 34, to accommodate 10 part of the coupler key 24 when the parts are assembled, as shown in Figures 1 and 2.

In order to provide for a detachable key connection between the coupling 31 and the hooded yoke, I employ a special member 15 designated generally by the reference A. Said member A has an elongated main section 35 cylindrical on the top and flat on the bottom, said section having an axially extending circular opening 36 of a size corresponding to the cylindrical shank 32 of 20 the coupling 31. At its rear end, the member A is formed with an integral heavy nut 37, the latter being interiorly threaded to cooperate with the threaded section 33 of 25 the coupling shank. The main section 35 of the member A is transversely slotted, as indicated at 38, to accommodate the coupler key 24, and it will be noted that the opening or slot 38 is at such a level as to bring the 30 upper part of the coupler key 24 partly within the longitudinally extending opening 36 so as to engage the recessed portion 34 of the coupling shank.

At its forward end the member A is provided with an extended foot 39 adapted to always engage and slide upon the horizontal surface 30 provided by the carry iron. Said foot 39 is connected to the main section 35 of the member A by an inclined web 40 and bracing side flanges 41-41.

As will be understood by those skilled in the art, the member A is so designed that when the coupling 31 is threaded home therein, the hook portion of the coupling 31 45 will be positioned in its proper position both with regard to height above the rail and its distance from the end sill of the car. And, furthermore, the rear end of the member A will normally abut against the 50 front follower 17 when the parts are in their normal or full release position. By forming a nut section 37 on the member A, I facilitate the assembling of the coupling and the member A, since the use of a 55 wrench is thereby permitted. By recessing the coupling shank and fitting the key therein, as hereinbefore described, rotation of the coupling 31 with respect to the member A is positively prevented.

With the construction hereinbefore described, it is evident that the coupling 31 is detachably associated with the yoke and the draft gear and the coupling may be removed in the same manner that a standard 60 key-slotted automatic coupler is removed.

The automatic coupler indicated by dotted lines at 42 will ride directly upon the carry iron and may be attached to the yoke in the usual manner customary in the United States. The employment of the forwardly 70 extended foot on the member A enables me to maintain the coupling 31 at its proper height while at the same time permitting of the necessary clearance at the end sill and carry iron to accommodate the much 75 heavier shank of an automatic coupler.

I have herein shown and described what I now consider the preferred manner of carrying out the invention but the same is merely illustrative and I contemplate all 80 changes and modifications that come within the scope of the claims appended hereto.

I claim:

1. In a railway draft rigging, the combination with a hooded yoke; of a coupling 85 having a shank transversely recessed intermediate its ends; an intermediate member disposed within the yoke hood and having a longitudinally extending opening within which said shank is received and provided 90 also with a transversely extending opening; and a key extending through said opening of said member and engaging said shank within said recess of the latter.

2. In a railway draft rigging, the combination with a hooded yoke having key slots in the side walls of the hood, of a hook coupling having a shank of cylindrical form at its inner end; and devices for operatively detachably connecting the shank of said 100 coupling and hood including a member extending within the hood, means for detachably connecting said shank and member, and a key extending through said member and the slots of the hood at a point forwardly 105 of the connection between said shank and said member.

3. In a railway draft rigging, the combination with a hooded yoke having key slots in the side walls of the hood; of a hook coupling having a shank of cylindrical form at its inner end; and means for operatively detachably connecting the shank of said coupling and hood including a member extending within the hood to which said shank 115 is detachably connected and a key extending through said member and the slots of the hood, said shank having a flattened recessed portion and said key engaging said recessed portion to thereby prevent turning of the 120 coupling with respect to said member.

4. In a railway draft rigging, the combination with draft sills, carry iron, stop acting means, shock absorbing means proper, and yoke acting means including portions having slots therein to accommodate a horizontally extending coupler key; of a coupler having a shank; a member to which the inner end of said shank is detachably directly connected, said member having a forwardly 125 130

- extended foot engaging and adapted to ride back and forth on said carry iron; and a key extending through said member and said slots in the yoke acting means.
5. As an article of manufacture, a transition coupling member adapted to act as an intermediary detachable connector between a slotted hood yoke and a coupler having a head and an integral elongated shank with a threaded portion at the inner end thereof, said threaded portion being disposed inwardly of the end sill structure of the car when the coupler is in operative position and said member being also disposed inwardly of the end sill structure of the car when in operative position, said member having a longitudinally extending opening therein to receive the coupler shank and provided with a threaded section to cooperate with said threaded section of the shank when the coupler and said member are in the positions aforesaid, said member being also transversely slotted to receive a key for connection with a slotted hood yoke.
6. As an article of manufacture, a member adapted to act as an intermediary detachable connector between a slotted yoke and a coupler having a shank, said member having a longitudinally extending opening adapted to receive said coupler shank and slots to receive a coupler key, said member being provided also with a forwardly extended foot adapted to slidably engage a carry iron.
7. As an article of manufacture, a member adapted to act as an intermediary detachable connector between a slotted yoke and a coupler having a threaded shank, said member having a longitudinally extending opening therein to receive the coupler shank and provided with a threaded section to cooperate with the threaded portion of the shank, said member being also transversely slotted to receive a key for connection with the slotted yoke, said member having a forwardly extended foot adapted to slidably engage a carry iron.
8. As an article of manufacture, a member adapted to act as an intermediary detachable connector between a slotted hood yoke and a coupler having a threaded shank, said member having a longitudinally extending opening adapted to receive the coupler shank and provided with a threaded section to cooperate with the threaded portion of the shank, said member being also transversely slotted to accommodate a coupler key, the transverse slot partially coalescing with said longitudinally extending opening, at a point forwardly of the threaded section.
9. In a railway draft rigging having draft sills, the combination with a yoke proper adapted to be disposed between the draft sills and inwardly of the outer ends of the draft sills; of a coupling having a head and an integral shank, the head being disposed outwardly of the ends of the draft sills and the shank extending to a point inwardly of the ends of the draft sills; an intermediate member disposed inwardly of the ends of the draft sills when in operative position; means detachably connecting said shank and said member at a point inwardly of the ends of the draft sills; and means detachably connecting said member and yoke proper at a point inwardly of the ends of the draft sills.
- In witness that I claim the foregoing I have hereunto subscribed my name this 8th day of Sept., 1920.
- CHARLES E. DATH.
